Attorney

UNITED STATES PATENT OFFICE.

ALBERT H. CARRIER, OF ASHEVILLE, NORTH CAROLINA, ASSIGNOR OF ONE-HALF TO
EDWIN W. GROVE, OF ST. LOUIS, MISSOURI.

METHOD OF PRODUCING A SHEATHING OR SHINGLE AND THE PRODUCT.

Application filed September 9, 1921. Serial No. 499,411.

To all whom it may concern:

Be it known that I, ALBERT H. CARRIER, a citizen of the United States, residing at Asheville, in the county of Buncombe and State of North Carolina, have invented new and useful Improvements in Methods of Producing a Sheathing or Shingle and the Product, of which the following is a specification.

10. This invention relates to an improved method of producing a palmetto or natural product sheathing or shingle, and the primary object in view is to conserve the natural tough fibrous characteristics of palmetto and the inherent flexibility thereof and render the same practicable for service as a sheathing or shingle covering for buildings and other analogous purposes at a comparatively small cost, and to produce a resultant product that will be moisture proof and much stronger and more durable than the natural material from which the product is made, and whereby a building material may be manufactured at a much less cost than by the use of ordinary lumber for a similar purpose. A further object of the invention is to provide a product from natural growths that have heretofore been considered commercially useless and take advantage of the strength and durability of the tough fiber that is embodied in palmetto and other similar coarse growths and subject the latter to such treatment as to essentially increase their strength and durability.

20. The invention consists in the several steps pursued in the preparation of the product and in the product itself as will be more fully hereinafter described and claimed.

25. In the drawing:

30. Fig. 1 illustrates a sectional view of a tank or receptacle in which the material may be prepared in accordance with the method embodying the features of the invention;

35. Fig. 2 is a detail perspective view of a strip or shingle after treatment in accordance with the improved method;

40. Fig. 3 is a view similar to Fig. 2, showing the surface of the strip or shingle supplied with a covering of material to give it the appearance of stone or other surface ornamentation.

45. The tank or receptacle shown by Fig. 1 is only one means of carrying out the method, and it will be understood that this simplified apparatus is not to be confined to any particular size or dimensions or exact details of construction, it being proposed to use a tank or receptacle of various types for effecting the steps of the method, or in manufacturing the product by the improved method. The tank or receptacle as shown comprises a body 5 of an air-tight character having a lid or cover 6 that may be opened or closed and tightly sealed when closed. An air exhaust connection 7 is attached to the tank or receptacle and provided with a valve 8, whereby the same may be closed, a suitable pipe or connection from an air pump or exhausting apparatus being applicable to the pipe 7 for creating a vacuum within the tank or receptacle. The tank or receptacle also has a valved inlet 9 for the admission of certain treating material into the tank or receptacle, as will be hereinafter specified. Within the body of the tank or receptacle 5 at a suitable elevation a supporting rack 10 is mounted for supporting the material to be treated, but it will be understood that the treatment of the material is not limited to the use of this rack, as other means may be employed for holding or supporting the material to the best advantage within the receptacle.

50. In carrying out the method the material to be treated, preferably pieces of palmetto of the desired thickness as at 11, are placed within the tank or receptacle 5, as for instance on the rack 10, and connection is made with the pipe 7 to an air pump or air exhaust mechanism and the valve 8 opened. After the material 11 is placed within the tank or receptacle 5, the cover 6 is sealed, to render the joints between the same and the receptacle air-tight, and after the apparatus has thus been prepared, the air is exhausted from the interior of the receptacle.

55. Fig. 2 is a detail perspective view of a strip or shingle after treatment in accordance with the improved method;

60. Fig. 3 is a view similar to Fig. 2, showing the surface of the strip or shingle supplied with a covering of material to give it the appearance of stone or other surface ornamentation.

65. The tank or receptacle shown by Fig. 1 is only one means of carrying out the method, and it will be understood that this simplified apparatus is not to be confined to any particular size or dimensions or exact details of construction, it being proposed to use a tank or receptacle of various types for effecting the steps of the method, or in manufacturing the product by the improved method. The tank or receptacle as shown comprises a body 5 of an air-tight character having a lid or cover 6 that may be opened or closed and tightly sealed when closed. An air exhaust connection 7 is attached to the tank or receptacle and provided with a valve 8, whereby the same may be closed, a suitable pipe or connection from an air pump or exhausting apparatus being applicable to the pipe 7 for creating a vacuum within the tank or receptacle. The tank or receptacle also has a valved inlet 9 for the admission of certain treating material into the tank or receptacle, as will be hereinafter specified. Within the body of the tank or receptacle 5 at a suitable elevation a supporting rack 10 is mounted for supporting the material to be treated, but it will be understood that the treatment of the material is not limited to the use of this rack, as other means may be employed for holding or supporting the material to the best advantage within the receptacle.

70. In carrying out the method the material to be treated, preferably pieces of palmetto of the desired thickness as at 11, are placed within the tank or receptacle 5, as for instance on the rack 10, and connection is made with the pipe 7 to an air pump or air exhaust mechanism and the valve 8 opened. After the material 11 is placed within the tank or receptacle 5, the cover 6 is sealed, to render the joints between the same and the receptacle air-tight, and after the apparatus has thus been prepared, the air is exhausted from the interior of the receptacle.

75. Fig. 2 is a detail perspective view of a strip or shingle after treatment in accordance with the improved method;

80. Fig. 3 is a view similar to Fig. 2, showing the surface of the strip or shingle supplied with a covering of material to give it the appearance of stone or other surface ornamentation.

85. The tank or receptacle shown by Fig. 1 is only one means of carrying out the method, and it will be understood that this simplified apparatus is not to be confined to any particular size or dimensions or exact details of construction, it being proposed to use a tank or receptacle of various types for effecting the steps of the method, or in manufacturing the product by the improved method. The tank or receptacle as shown comprises a body 5 of an air-tight character having a lid or cover 6 that may be opened or closed and tightly sealed when closed. An air exhaust connection 7 is attached to the tank or receptacle and provided with a valve 8, whereby the same may be closed, a suitable pipe or connection from an air pump or exhausting apparatus being applicable to the pipe 7 for creating a vacuum within the tank or receptacle. The tank or receptacle also has a valved inlet 9 for the admission of certain treating material into the tank or receptacle, as will be hereinafter specified. Within the body of the tank or receptacle 5 at a suitable elevation a supporting rack 10 is mounted for supporting the material to be treated, but it will be understood that the treatment of the material is not limited to the use of this rack, as other means may be employed for holding or supporting the material to the best advantage within the receptacle.

90. In carrying out the method the material to be treated, preferably pieces of palmetto of the desired thickness as at 11, are placed within the tank or receptacle 5, as for instance on the rack 10, and connection is made with the pipe 7 to an air pump or air exhaust mechanism and the valve 8 opened. After the material 11 is placed within the tank or receptacle 5, the cover 6 is sealed, to render the joints between the same and the receptacle air-tight, and after the apparatus has thus been prepared, the air is exhausted from the interior of the receptacle.

95. Fig. 2 is a detail perspective view of a strip or shingle after treatment in accordance with the improved method;

100. Fig. 3 is a view similar to Fig. 2, showing the surface of the strip or shingle supplied with a covering of material to give it the appearance of stone or other surface ornamentation.

105. The tank or receptacle shown by Fig. 1 is only one means of carrying out the method, and it will be understood that this simplified apparatus is not to be confined to any particular size or dimensions or exact details of construction, it being proposed to use a tank or receptacle of various types for effecting the steps of the method, or in manufacturing the product by the improved method. The tank or receptacle as shown comprises a body 5 of an air-tight character having a lid or cover 6 that may be opened or closed and tightly sealed when closed. An air exhaust connection 7 is attached to the tank or receptacle and provided with a valve 8, whereby the same may be closed, a suitable pipe or connection from an air pump or exhausting apparatus being applicable to the pipe 7 for creating a vacuum within the tank or receptacle. The tank or receptacle also has a valved inlet 9 for the admission of certain treating material into the tank or receptacle, as will be hereinafter specified. Within the body of the tank or receptacle 5 at a suitable elevation a supporting rack 10 is mounted for supporting the material to be treated, but it will be understood that the treatment of the material is not limited to the use of this rack, as other means may be employed for holding or supporting the material to the best advantage within the receptacle.

and the mechanical vacuum gradually produced will at the same time draw out the natural moisture contained in the material 11 and more or less open up the pores of the 5 same. The material treated is left in the tank under the action of the vacuum for about twenty-four hours, and after this period the valve 8 is closed and the valved inlet 9 is opened, a connection having been 10 made between this valved inlet and a supply source containing hot asphalt. The asphalt will rapidly enter the interior of the tank 5 and submerge the material 11 which has been previously subjected to the action 15 of the vacuum, and this submergence of the material within the hot asphalt will continue for a period sufficient to set up a thorough impregnation of the material by the asphalt, or until the asphalt has fully saturated the said material 11. After this saturation of the material 11 with the asphalt, the natural pithy filling of the palmetto or natural coarse growth will be completely 20 permeated with the asphalt and a greater 25 body strength will be given to the material treated. Subsequent to this treatment of the material with the asphalt for a sufficient period to effect thorough saturation as explained, the asphalt saturated material is 30 removed from the receptacle and allowed to become dry or cured and may then be used as a shingle covering or as a surface sheathing in accordance with the size of the pieces of material so treated. 35 The asphalt renders the material water proof and also strengthens and increases the durability of the natural product. If desired, the saturated or cured product may be painted, or prior to the full drying operation thereof various kinds of stone in comminuted form or pebbles may be applied to at least one surface of the saturated piece, to effect an adhesion of this covering by 40 means of the asphalt when the latter is fully dry. The comminuted stone or other covering material, including pebbles, may also be applied to at least one side of the piece of material treated by the addition of a suitable adhesive substance, and through the medium of this operation an advantageous 45 variation in the building material product will result. These surface coverings may be modified or varied as found desirable in accordance with the design of the building to 50

be constructed and in part at least with the improved material. 55

It is also proposed to use the improved material constructed in accordance with the foregoing method in all sorts of buildings where the same may be applicable and economically useful, and it is particularly effective in the construction of light buildings such as shacks and bungalows, which will be rendered water proof and also be thereby generally protected and also may be given an unique surface design appearance by the use of the material in its several forms. 65

What is claimed as new is:

1. The method of forming a building material, consisting in subjecting a piece of natural wood product having distinct strong fibers and a pithy filling to vacuum action within an enclosure until the material has moisture completely eliminated therefrom, 70

then saturating the material while in vacuum with hot asphalt, and removing the material from the enclosure and drying and curing the same. 75

2. The method of forming a building material, consisting in subjecting a piece of natural wood product having distinct strong fibers and a pithy filling to vacuum action within an enclosure until the material has moisture completely eliminated therefrom, 80

then saturating the material while in vacuum with hot asphalt, and removing the material from the enclosure and providing 85

the same with an adhering covering material. 90

3. As an improved article of manufacture, a natural wood product having a plurality of tough fibers extending therethrough and imbedded in a pithy filling saturated with asphalt completely therethrough to render 95 the material water proof. 95

4. A product consisting of a natural wood material having elongated tough fibers imbedded in a pithy filling thoroughly saturated and permeated with asphalt and provided with an adhering covering material. 100

In testimony whereof I have hereunto set my hand in presence of two subscribing witnesses.

ALBERT H. CARRIER.
